DESIGN FOR A HEATER

Victor H. Cope, Defiance, Ohio

Application October 29, 1934, Serial No. 53,815

Term of patent 7 years

To all whom it may concern:

Be it known that I, Victor H. Cope, a citizen of the United States, and residing at Defiance, in the county of Defiance and State of Ohio, have invented a new, original, and ornamental Design for a Heater, of which the following is a specification, reference being had to the accompanying drawing, forming a part thereof.

In the drawing:

Figure 1 is a perspective view of a heater showing my design.

Figure 2 is a side elevational view of the heater,

the deflector being shown in a different position of adjustment than that shown in Figure 1.

Figure 3 is a front elevational view of the heater, the deflector being in the same position of adjustment as shown in Figure 2.

I claim:

The ornamental design for a heater substantially as shown and described.

Signed at Defiance, in the county of Defiance and State of Ohio, this 25th day of October, 1934.

VICTOR H. COPE.
